Patented July 22, 1969

214,727

COMBINATION TENT AND CAR-TOP CARRIER APPARATUS

Sidney L. Perry, 5145 Kelvin Ave.,
Los Angeles, Calif. 91364

Filed May 21, 1968, Ser. No. 12,035

Term of patent 14 years

Int. Cl. D21—05; D12—14

U.S. Cl. D14—27

Fig. 1

Fig. 2

Fig. 3

Fig. 4

FIGURE 1 is a rear, top and right side perspective view of combination tent and car-top carrier apparatus in an open position, showing my new design;

FIGURE 2 is a front, top and left side perspective view thereof in an open position;

FIGURES 3 and 4 are respectively rear and front elevation views thereof in an open position;

FIGURE 5 is a perspective view thereof in a closed position in the same aspect as FIGURE 1;

FIGURE 6 is a right side elevation view thereof in a closed position; the left side, not shown in this position, is a mirror image of the right side;

FIGURES 7 and 8 are respectively rear and front elevation views thereof in a closed position; and

FIGURE 9 is a top plan view thereof in a closed position.

I claim:

The ornamental design for a combination tent and car-top carrier apparatus, substantially as shown and described.
